UNITED STATES PATENT OFFICE

2,580,302

FLUID TYPE SWITCH

Vincent W. Jones, Cleveland Heights, Ohio

Application January 2, 1948, Serial No. 289

12 Claims. (Cl. 200—152)

1

This invention relates to fluid type switches for making and breaking electric circuits and particularly to a mercury switch of the general type having a body of insulating material in the ends of which are electrodes which are electrically insulated from each other by the body and in which a body of mercury, or other liquid conductor, within the body forms a bridge between the electrodes for making the circuit in one position of the body.

Heretofore, electrical switches of the general type described have been provided, a typical example being one such as illustrated in U. S. Letters Patent No. 2,101,093, issued to John H. Payne on December 7, 1937.

The electrical switch elements of switches such as described in the above patent are usually sealed so as to prevent the escape of the mercury therefrom and to prevent the ingress of air, the general purpose of excluding air being to reduce the deleterious effects of arcing caused by making and breaking contact. Frequently, they are filled with non-oxidizing gas. However, such switch elements have limitations which reduce their field of applicability to use with relatively small currents, for example, to a maximum of about 5 amperes, at 110 volts, of alternating current, though they have proven satisfactory below this maximum.

However, they are subject to arcing and when used at higher amperage currents such as 20 to 25 amperes at 110 volts, the arcing causes rapid deterioration of such switch elements, frequently heating the confined air or gases so rapidly that the switch elements are blown apart. Again, the effects of arcing on the mercury and electrodes are such that they become useless for their intended purposes.

Furthermore, such switches are limited as to the position in which they can operate.

One of the principal objects of the present invention is to provide a switch of the general character described which is less subject to arcing than the prior mercury switches and in which the deleterious effects caused by any arcing which does occur are greatly reduced or substantially eliminated.

Another object is to provide a switch of the general type described which may be used in any number of rotated positions about its own axis throughout an angle of 360° and which operates effectively when its normal axis of rotation is tilted as much as 25° in either direction from the horizontal.

A more specific object is to provide a mercury switch capable of more rapid making and breaking of contact, and of initial making and breaking over a larger contact area, whereby the arcing is reduced.

2

A more specific object is to provide an improved electrode for contact with the mercury in such a switch.

Other objects and advantages will become apparent from the following description wherein reference is made to the drawings in which:

Fig. 1 is a side elevation of a switch embodying the principles of the present invention;

Fig. 2 is a front elevation of the switch illustrated in Fig. 1;

Figs. 3 and 4 are sectional views of the switch illustrated in Figs. 1 and 2 and are taken on lines 3—3 and 4—4, respectively, of Figs. 1 and 2, respectively;

Fig. 5 is a perspective view of the mercury switch element of the present invention;

Fig. 6 is a left end elevation of the body of the switch element illustrated in Fig. 5 showing the same in the "on" position, part thereof being shown in section for clearness in illustration;

Figs. 7 and 8 are sectional views taken on the lines 7—7 and 8—8, respectively, of Fig. 6, the mercury being shown in Fig. 7 for clearness in illustration;

Fig. 9 is a side elevation of a modified form of switch embodying the principles of the present invention;

Fig. 10 is a fragmentary sectional view taken on the line 10—10 of Fig. 9; and

Figs. 11 and 12 are right end elevations of the switch element illustrated in Fig. 10 showing it in the "on" and "off" positions respectively.

Referring to the drawings, a switch is shown for the purposes of illustration as mounted in the usual outlet box B such as is customarily used for household light switches.

The switch comprises generally a body 1 which may be of synthetic plastic or other moldable plastic material of an insulating character. The body 1 has secured thereto a suitable supporting strap 2 which is adapted to be connected to the box B for supporting the body 1 in proper position therein. The body 1 has a transverse cylindrical bearing surface 3 in which is rotatably mounted the switch element, later to be described.

Rotatably supported in the bearing surface 3 is a cylindrical bearing sleeve 4 of insulating material which likewise may be organic or synthetic plastic, such as cellulose acetate or acrylic resin. The sleeve 4 has a radially extending handle 5 which may be integral therewith and which is adapted to be swung about the axis of the bearing surface 3 from an upper "off" position of the switch to a lower "on" position. Suitable springs 7 are mounted on the strap 2 at each side of the handle 5. Each spring 7 has a curved portion 8 which is convex toward the axis of the bearing 3 in a position to be engaged by a cooperating lug

9 on the sleeve 4. The convex portions 8 are arranged at opposite sides of the mid-position of the handle 5 between off and on positions, and bear against their associated lugs 9 as the sleeve 4 is rotated initially from mid-position in either direction. Thus they yieldably oppose initial movement of the sleeve partway from mid-position of the handle 5 to "on" and "off" positions and suddenly release the opposing force after a predetermined movement so that the switch will be moved rapidly to fully "on" or "off" position by the operator.

The sleeve 4 may be constrained from radial displacement from the bearing surface 3 by making the bearing of sufficient circumferential extent to embrace more than 180° of the sleeve, the sleeve being inserted endwise during installation. If desired, however, the bearing may be of less extent than 180° so that the sleeve is held in position by the force of the springs 7.

A mercury switch element, designated generally at 10, with which the present invention is particularly concerned is generally cylindrical and is mounted in the sleeve 4 for rotation therewith. Preferably it is held firmly in the desired rotated position relative to the sleeve 4 by a press fitting engagement therewith. However, the element 10 can be removed from the end of the sleeve by hand pressure and reinserted in any rotated position relative to the sleeve so that the element will be in the proper operating position regardless of the angle about the axis of the surface 3 at which the strap 2 supports the body 1.

Referring next to the mercury switch element 10, it comprises a body 11 which preferably is in the form of an open end cylinder formed of rigid insulating material, such as glass, Bakelite, synthetic resin, though porcelain with an impervious shiny or vitrified surface is preferred. The body 11 has partition walls 12 and 13 which are spaced apart axially of the body from each other and inwardly from the respective ends of the body so as to define end contact chambers 14 and 15, respectively, and an intermediate expansion chamber 16.

The ends of the chambers 14 and 15 are closed by suitable electrodes 17 and 18, respectively, which are sealed to the body 11. The electrodes are preferably concave on their entire inner surfaces, as illustrated, so that the chambers 14 and 15 are of gradually decrescent horizontal cross section from their centers to their circumferences. It has been found that soft annealed nickel is the most suitable material for the electrodes in that it has a greater conductivity than hard nickel and less adherence to mercury. Mercury tends to combine or amalgamate with most metals, particularly under the heat of an arc caused by operation of the usual mercury switches and often dissolves or removes small particles of other metal when heated and reheated by the arc, eventually breaking down the metal entirely or rendering its contact surface undesirable. No such amalgamation or deleterious effects appear to result when soft annealed nickel is used.

The partition walls 12 and 13, which are shown as parallel with each other and at right angles to the axis of the element are provided with passages 19 and 20 respectively, the passages being eccentric to the axis of the body 11. The passages 19 and 20 extend entirely through their associated walls 12 and 13 so as to afford a passage for mercury between the chambers 14, 15, and 16, when the element 10 is rotated to dispose the passages 19 and 20 below the level of the mercury

contained in the chambers. On the side of the partition wall 12 exposed in the chamber 14 there is a concavity 21 which, as best illustrated in Fig. 7, is generally oval shaped with the major axis of its periphery disposed at an angle to a radius from the axis of the body 1 through the axis of the passage 19. The concavity is arranged so that its periphery surrounds the end of the passage 19 and so that its deepest portion is at the periphery of the end of the passage 19. A similar concavity 22 is provided in the partition wall 13 on the face exposed in the end contact chamber 15.

The expansion chamber 16 is of greater diameter than the end chambers 14 and 15 and is preferably coaxial therewith and of greater capacity than the sum of the capacities of the chambers 14 and 15. For example, the contact chambers may be about 0.650 inch in diameter and $\frac{1}{16}$ of an inch wide at the axis and the expansion chamber may be approximately 0.725 inch in diameter and about $\frac{1}{4}$ inch wide. In a structure of this size, the walls 12 and 13 each may be about $\frac{1}{8}$ of an inch thick with a concavity about $\frac{1}{16}$ of an inch maximum depth. In their lowermost position the passages 19 and 20 preferably are angularly positioned about 10° in advance of the vertical in the "off" direction when the switch is in the "on" position.

The chambers are filled with mercury, indicated at 23, to a depth such that when the element 10 is rotated to dispose the passages 19 and 20 in their lowermost position, the level of the mercury is above the top of the passages 19 and 20 an appreciable amount. Usually this results in a mercury level just below the axis of the body 11. In "on" position the mercury forms in a continuous body from one electrode to the other through the chambers 14 and 15, the passages 19 and 20 and the expansion chamber 16. As a result, when the element 10 is in "on" position the passages 19 and 20 are completely blocked by the mercury and prevent any air or gases lying above the level of the mercury from passing from one chamber to the other. The chamber 16 has in its circumferential wall a small capillary duct or vent 24 which is preferably arranged so as to be above the level of the mercury at all times, or it may be diametrically opposite from the passages 19 and 20. The vent 24 vents the chamber 16 to the outside atmosphere and is preferably of such size that the mercury cannot run out of it under the force of gravity.

In order to prevent accidental displacement of mercury from the chamber 16 through the vent 24, as by severe shaking of the element 10, the body 11 is provided with an outwardly open peripheral channel 25 which is filled with rock wool 26 or other packing which tends to obstruct the passage of the mercury yet affords a sufficient passage for air. A retaining sleeve 27 is press fitted over the body 11 for retaining the packing in place in the channel 25 and suitable grooves 28 are provided on the exterior of the body 11 and extend from the channel generally endwise of the body to the end of the body 11 so as to be in communication with the outside air.

The element 10 is complete in and of itself and may be readily replaced in the switch by pressing it by hand pressure into the sleeve 4.

In order to prevent axial displacement of the element 10 and the sleeve 4, contacts carried by the body are arranged to bear against the ends of the electrodes 17 and 18. As illustrated in Fig. 3, for example, one contact 29 bears against

the electrode 17 and is fixedly secured to the body 1 of the switch and is adapted for connection to an electric power line. Correspondingly, a contact 31 is connected to the body 1 and bears against the electrode 18 and is adapted for connection to a power line. The contacts 30 and 31 are preferably formed of metal having sufficient springiness to press positively against the associated electrodes, thus not only holding the switch element 10 in position but also assuring a firm electrical contact.

In operation, the switch body 1 as a whole is installed in any rotated position desired about the axis of the bearing surface 3. The sleeve 4 is installed by moving it endwise into the bearing surface 3 axially thereof. The handle 5 may then be moved to the "on" position and while held in this position, the element 10 may be pressed into the sleeve 4 while its passages 19 and 20 are disposed below the axis of the element and 10 degrees in advance of the vertical through the axis, this being all the adjustment necessary for the switch when installed in the particular position desired. Suitable indicia or graduations may be marked on the ends of the body 11 and sleeve 4 to assist in indicating the proper rotated relation of the sleeve and body. Obviously, with this adjustment, the switch body 1 can be installed in any rotated position about its axis throughout 360° and the element 10 installed therein for proper operation.

Due to the large capacity of the chamber 16 relative to the chambers 14 and 15, the switch operates effectively even though the horizontal axis is tilted as much as 25° from the horizontal.

Due to the arrangement of the concavities 21 and 22, the surface tension of the mercury, or its capillary attraction to the walls 12 and 13, breaks when the periphery of the concavity passes below the mercury surface and the mercury then starts travelling toward the passages 19 and 20 before such passages have been moved below the mercury level. This gives the mercury an initial velocity toward the passages 19 and 20.

Due to the positions of the concavities, this tends to cause a flow of the mercury generally upwardly toward the passages when the switch is suddenly switched to an "on" position. At the same time, however, it causes a pool of mercury to accumulate rapidly just beneath the passages so as to provide a large contact surface for any mercury flowing out of the passages into the contact chambers.

On the other hand, since the chamber 16 is of larger diameter than the contact chambers, the mercury tends to flow more rapidly down its steeper circumferential wall, and in a larger volume toward the passages 19 and 20, when the element 10 is rotated from "off" to toward "on" position. This, and possibly because the chamber 16 is vented, causes the mercury to discharge rapidly from the expansion chamber 16 through the passages 19 and 20 with a substantial initial velocity. As a result of these effects, the mercury flows from the expansion chamber through the passages 19 and 20 into the contact chambers an instant before the mercury in the contact chambers reaches the openings 19 and 20. Consequently, the upwardly rising stream of mercury in the contact chambers and the laterally flowing stream from the passages 19 and 20 meet just outside of those ends of the passages 19 and 20 which are in the contact chambers. These streams, thus meeting at an

angle, make substantially instantaneous contact over a large area without surging. Likewise, on turning the switch to "off" position, the contact is broken in the contact chamber.

Since any arcing that would occur must occur when the contact is made or broken, it occurs while the passages 19 and 20 are blocked to exclude air by the mercury. Should any arcing occur, the expansion of the gases in the contact chambers is relieved by forcing the mercury downward therein and raising slightly the mercury level in the expansion chamber, the air above the mercury in the latter being vented through the vent 24.

While air can pass from the expansion chamber to the contact chambers while the switch is in "off" position, no appreciable introduction of fresh air appears to result, apparently due to the fact that the air capacity of the expansion chamber above the level of the mercury is so large that the air passing into the contact chambers therefrom is merely returned to the expansion chamber when the switch is turned to "on" position.

In general, it has been found that the level of the mercury in the expansion chamber 15 should be just below the center line of the chamber and that the electrodes always should be in contact with the mercury over a substantial part of their surface. For the purposes of illustration, the walls 12 and 13 have been shown as of uniform thickness, except for the concavities, and at right angles to the axis of the element 10 with the passages 19 and 20 eccentric to the axis of the element 10. Obviously, in the broader aspects of the invention so far as it relates to venting, the passages may be made concentric with the axis of the element 10 and the walls 12 and 13 set on a bias to the axis of

the element 10, or made thicker at one portion than at a diametrically opposite portion, so that in the "on" position the thicker wall portions are at the bottom and consequently the chambers 14, 15, and 16 are relatively narrower at the

bottom portion than at the top portion. Thus the level of the mercury is caused to rise so that the mercury overflows the passages 19 and 20 when the narrow portions of the chambers are at the bottom and accommodate mercury, and is caused to lower when the wider portions of the chambers are disposed in a lower position and accommodate the mercury.

In Figs. 9 through 12, there is illustrated a modified form of the switch, and particularly of the mercury switch element in which latter the body is partly of metal so as to dissipate heat more rapidly, make and break contact is made between bodies of mercury, as distinguished from make and break contact directly between a body of mercury and the metal of the body, and make and break contact in the heat dissipating expansion chamber as distinguished from make and break contact in the contact chambers, is assured.

In this form of the invention the body 49 of the mercury switch element is similar to the body 11 heretofore described but is made of aluminum or other metal or material having good heat conduction and dissipating qualities.

The body is cylindrical and open at both ends and has at opposite ends counterbores in which are fitted and sealed electrical insulating cups or linings 41 and 42, respectively. The bottom walls of the cups provide insulating partition walls 43 and 44 which divide the interior of the

body 40 into end chambers 45 and 46 and an isolated intermediate expansion chamber 47.

The diameter of the chamber 47 is preferably slightly greater than the diameter of the chambers 45 and 46. The metal of the body 41 forms the peripheral wall of the chamber 47 and is exposed therein for contact with the mercury of the element.

The body 41 has a minute vent 48 leading from the chamber 47 to a peripheral channel 49 which may be filled with rockwool or other material and channels or grooves 50 leading from the channel 49 to the atmosphere, similar in form and function to channel 25 and grooves 28 heretofore described. The body is tightly fitted in a retaining sleeve 51 similar to the sleeve 21.

Electrodes 53 and 54 are seal fitted into the ends of the cups 40 and 41, respectively, and form the end walls of the end chambers 45 and 46. The electrodes are the same as the electrodes 17 and 18 heretofore described except that their outer end walls are dished for effecting better contact with the contacts 55 and 56, the contacting ends of which latter are convex toward the electrodes so as to fit the dished surfaces thereof and yieldably resist removal of the element radially from its open sided supporting bearing surface 57 of the support 58. The body 40, with its sleeve 51 are received endwise in a cylindrical bearing sleeve 59 having a handle 60. The body is held in fixed axial position and in any desired rotated position relative to the sleeve 59 by a set screw 61. The open front of the bearing is bridged by a dead center leaf spring 62 which is secured to the support 58 and cooperates with lugs 63 on the sleeve 59 to assure rotary movement of the switch element by the handle fully to "on" and "off" positions respectively.

The partition walls 43 and 44 have passages 65 and 66 therethrough, the passages preferably being aligned with each other endwise of the body 40 and, in the "on" position of the switch element are preferably at their lowest level which, as illustrated in Fig. 11 may be about twenty-five degrees from the vertical in the "off" direction, and are swung upwardly about fifty degrees to sixty degrees clockwise, when the element is viewed from the right in Fig. 10, to the position illustrated in Fig. 12 which is the "off" position of the element. It is noted that the position of the handle 60 is adjustable circumferentially of the body 40, as described, so that the switch as a whole can be placed in any position rotated about the axis of the bearing 57 and can operate properly in the selected position.

The axes of the passages 65 and 66 are not parallel to the axis of the body 40 but oblique thereto so that the open end of each of the passages in the expansion chamber 47 leads the other end thereof by a slight angle when the body 40 is rotated from an "on" to an "off" position.

Likewise the radially outermost limits of the passages 65 and 66 are substantially at the peripheral walls of the chambers 45 and 46, respectively, and radially inwardly slightly from the peripheral wall of the expansion chamber 47.

By this arrangement, when the switch element is rotated from "off" to "on" position, mercury will enter the passages 65 and 66 from the contact chambers 45 and 46 before it can enter from the expansion chamber 47. At the same time, since the volume of mercury in the expansion chamber is not temporarily reduced due to a portion entering the passages, the peripheral wall of the chamber 47 is covered with mercury adjacent the

ends of the passages 65 and 66 before any mercury can pass into the chamber 47 through the passages and by the time mercury enters the chamber 47 the area of coverage is great enough to assure contact of the entering mercury directly with the mercury already present in the chamber 47 instead of contact by the entering mercury with the bare peripheral metal wall. Correspondingly, upon rotation of the element in the opposite direction to "off" position, contact is broken in the chamber 47 between mercury covering the peripheral wall and mercury returning to the chambers 45 and 46 through the passages.

Thus there is never any make or break of contact between mercury and the metal of the body but only between portions of the mercury which are always in contact with the body and electrodes, respectively.

It is desirable that the contact of the mercury entering the chamber 47 be made with that already in the chamber 47 instantaneously over a large area and with a considerable volume. To assure such a large area and volume, shallow depressions 67 and 68 be provided in the outer surfaces of the partition walls 43 and 44. The depressions are arranged at approximately the same distance radially outwardly from the axis of the body as the adjacent ends of their associated passages 65 and 66 respectively, and each leads its associated passage by a small angle in the "on" direction with its relatively trailing boundary separated from the end of its associated passage by a narrow bridge or ledge, such as indicated at 70 in Fig. 11. Thus, in Fig. 11, before the open end of the passage 66 reaches the mercury level, mercury has accumulated in the depression 68 closely adjacent thereto sufficient in amount so that upon continued movement toward "on" position it is suddenly released and completely fills the open end of the passage 66, blocking the same against passage of air, and continues as a mass completely filling the passage and presenting initially in the chamber 47 a solid column of mercury of the full diameter of the passage 66 for making contact. Upon return toward "off" position it provides a readily available space to accommodate mercury so that contact is not apt to be broken between the mercury in the chamber 46 and that in the passage before the contact is broken in the expansion chamber 47.

Thus mercury to mercury making of contact in the expansion chamber is assured, and since any gases in expansion chamber can escape readily and the heat generated can be absorbed and then dissipated readily by metal to metal conduction, oxidation and deterioration of the mercury and metal of the switch is negligible.

Having thus described my invention, I claim:

1. A mercury switch element comprising a hollow body having contact chambers therein and an expansion chamber therebetween, electrodes in the contact chambers, respectively, mercury in all of said chambers, said body having passage means connecting the contact chambers with each other through the expansion chamber, said contact chambers being sealed except for said passage means, said chambers and passage means and volume of mercury being related so as to cause mercury to connect the electrodes together and block the passage means in one position of the body and to disconnect the electrodes from each other and unblock the passage means in another position of the body, and said body having a vent independent of the passage means and opening at one end directly into the

expansion chamber and connecting the expansion chamber with the atmosphere above the level of the mercury in the position of the body in which the passage means are blocked.

2. A mercury switch element according to claim 1 characterized in that the air vent is continuously open.

3. A mercury switch element according to claim 1 characterized in that said vent is a capillary passage through which the mercury will not flow out of the expansion chamber under the force of gravity.

4. A mercury switch element comprising tubular body, electrodes sealed in end portions thereof and insulated from each other thereby, a pair of partition walls dividing the body into end contact chambers and an intermediate expansion chamber, said walls each having a passage therethrough, mercury in said chambers, the passages and chambers being related so that the mercury is below the level of the passages when the body is in one rotated position about its axis and is above the top of the passages when the body is in another rotated position about its axis, and said intermediate expansion chamber being of larger diameter than the end chambers.

5. In an electric switch, a supporting body having an arcuate bearing surface therein, a sleeve fitting said surface and supported thereby for rotation about the axis of the sleeve, a generally cylindrical contact making and breaking mercury switch element adapted to make and break contact upon rotation about its axis to different positions, said switch element being adapted to fit snugly into the sleeve in coaxial relation therewith and for rotation therewith in a plurality of relatively rotated positions of the element and sleeve about the sleeve axis, said switch element being removably accommodated in and supported by the sleeve in coaxial relation therewith and for rotation therewith, means operatively connected to the sleeve for rotating the sleeve in opposite directions, and contacts carried by the body and in electrical contact with the said contact surfaces, respectively.

6. A mercury switch element comprising a tubular body, electrodes sealing the ends of the body, partition walls in and spaced apart from each other and from the ends of the body and dividing the body interior into end contact chambers and an intermediate expansion chamber, said end chambers being insulated from each other, each partition wall having a passage therethrough in eccentric relation to the axis of the body, mercury in said chambers, the chambers, passages and amount of mercury being so related that the mercury is sufficient to fill the chambers above the level of the passages when the body is in a horizontal position with the passages disposed in a lower position and insufficient to reach up to the level of the bottom of the passages when the body has been rotated to dispose the passages a predetermined distance above said lower position, and said body having a continuously open vent independent of said passages and opening at one end directly into the expansion chamber and connecting the expansion chamber with the atmosphere above the level of the mercury in the position of the body in which the passages are blocked.

7. A mercury switch element comprising a tubular body, electrodes sealing the ends of the body, partition walls in the body and spaced apart from each other and from the ends of the body and dividing the body interior into end con-

tact chambers and an intermediate expansion chamber, said end chambers being insulated from each other, each partition wall having a passage therethrough in eccentric relation to the axis of the body, mercury in said chambers, the chambers, passages and amount of mercury being such that the mercury is sufficient to fill the chambers above the level of the passages when the body is in a horizontal position with the passages disposed at a lower position and insufficient to reach up to the level of the bottom of the passages when the body has been rotated to dispose the passages a predetermined distance above said lower position, and each of said partition walls having, in the face exposed in its associated end contact chamber, a concavity adjacent its passage and wider radially of the face than its passage.

8. The switch element according to claim 7 characterized in that said concavity is of greater area than the end of the adjacent passage and slopes from all points of its periphery toward said adjacent passage.

9. The switch element according to claim 7 characterized in that the concavity entirely surrounds the end of the adjacent passage.

10. The switch element according to claim 7 characterized in that the passage opens into the deepest part of the concavity.

11. The mercury switch element according to claim 9 characterized in that the concavity is oval shaped and the major axis of the periphery of the concavity is disposed at an angle to a radius from the axis of the wall through the center of the passage.

12. A mercury switch element comprising tubular body, electrodes sealed in end portions thereof and insulated from each other thereby, a pair of partition walls dividing the body into end contact chambers and an intermediate expansion chamber, said walls each having a passage therethrough, mercury in said chambers, the passages and chambers being related so that the mercury is below the level of the passages when the body is in one rotated position about its axis and is above the top of the passages when the body is in another rotated position about its axis, said intermediate expansion chamber being of larger diameter than the end chambers, and said body having a continuously open vent independent of said passages and opening at one end directly into the expansion chamber and connecting the expansion chamber with the atmosphere above the level of the mercury, in the position of the body in which the passages are blocked.
